UNITED STATES PATENT OFFICE

148,519

DESIGN FOR AN ATHLETIC SHOE OR THE LIKE

Michele Campagna, Bristol, R. I., assignor to Bristol Manufacturing Corporation, Bristol,
R. I., a corporation of Rhode Island

Application January 11, 1947, Serial No. 136,087

Term of patent 14 years

(Cl. D7—7)

To all whom it may concern:

Be it known that I, Michele Campagna, a citizen of the United States of America, residing at Bristol, county of Bristol, and State of Rhode Island, have invented a new, original, and ornamental Design for an Athletic Shoe or the like, of which the following is a specification, reference being had to the accompanying drawing, forming a part thereof.

Fig. 1 is a side elevational view of the inner side of an athletic shoe or the like, showing the essential features of my design in full lines; and

Fig. 2 is an elevational view of the outer side of the same.

I claim:

The ornamental design for an athletic shoe or the like, substantially as shown and described.
MICHELE CAMPAGNA.
